UNITED STATES PATENT OFFICE.

JOHN M. HANSEN, OF PITTSBURG, PENNSYLVANIA.

SIDE AND CENTER DUMP COKE-CAR.

SPECIFICATION forming part of Letters Patent No. 752,289, dated February 16, 1904.

Application filed August 13 1903. Serial No. 169,379. (No model.)

To all whom it may concern:

Be it known that I, JOHN M. HANSEN, a resident of Pittsburgh, in the county of Allegheny and State of Pennsylvania, have invented a new and useful Improvement in Side and Center Dump Coke-Cars; and I do hereby declare the following to be a full, clear, and exact description thereof.

My invention relates to railway-cars, and more especially to cars of the hopper-bottom type designed for carrying coke, coal, and similar substances.

The object of my invention is to improve a car of the kind above specified in details of construction hereinafter described and claimed.

In the accompanying drawings, Figure 1 is a plan view of one-half of the car, showing the roof removed on the lower half of said figure. Fig. 2 is a horizontal section exposing the underframe. Fig. 3 is a side view of one-half of the car. Fig. 4 is a longitudinal vertical section of one-half of the car, its end portion being taken at the transverse center of the car and its other portion being taken through one of the hoppers. Fig. 5 is a transverse section of the car on the line 5-5, Fig. 1. Fig. 6 on its left-hand portion is an end view of the car and on the right-hand portion a transverse section on the line 6-6, Fig. 1.

The underframe comprises center sills 1, body-bolsters 2, draft-beams 3, end sills 4, and suitable connecting members therefor. The center sills may be of any type and are shown as rolled channel-beams placed with their flanges toward each other. They extend slightly beyond the body-bolsters 3, and to the ends thereof are spliced the draft-sills 4, the latter extending outwardly slightly beyond the end sill. The end sill is a rolled channel placed with its flanges projecting inwardly and being notched at its lower side to permit the draft-beams to pass through the same. A hood 5, of pressed metal, is riveted to the end sill at the center of the car and serves to support the outer ends of the draft-beams. This hood is provided with an opening 6 for the passage of the draw-bar shank and supports the draw-bar carrier 7.

The body-bolster is composed of a web-plate 8, extending from side to side across the car

and in height extending from the bottom of the center sills to a considerable distance above the same. This web-plate is flanged at its upper edge, as at 10, to provide a support for the inclined floor-plates 11. Extending from side to side of the car a considerable distance above the center sills and in proximity to the upper edge of the web-plate are a pair of flanged bars 13, shown as angles, which, in effect, form the tension member of the bolster. The web-plate 8 is secured to the center sills by sections of vertical angle-bars 14 and to the car sides by similar members 15, these angle-bars rising as high as the horizontal angle-bars 13 and serving also to stiffen the web-plate. The web-plate is further stiffened by vertical angle-bars 16. To the lower edge of the web-plate 8 are connected sections of angle-bar 17, which extend from the center sills to the car sides. Between the center sills is placed the usual brace 18, and a transverse tie member or cover-plate extends underneath the center sills out toward the car sides and is riveted to the angle-bars 17, secured to the lower edges of the web-plates. This cover-plate serves to strengthen the compression member of the bolster and has the usual center plate and side bearings riveted thereto.

Diagonal braces 20 extend from the corners of the car inwardly to the center sills and bolster, being secured at their outer ends to gusset-plates 21, riveted to the corners of the car, and at their inner ends to connection-plates 22, secured to the webs of the draft-sills and to the web-plates of the body-bolster. The parts of the car so far described are substantially the same as heretofore used and patented by me, and the specific construction of the parts which have been shown have been selected for purposes of illustration merely, it being understood that they may be varied within limits to suit the convenience of the builder or user.

The car has no distinct side sills, but the sides of the car-body serve both as side sills and car sides. These sides are of a compound type, being partly plate-girders and partly truss-girders. Each car side comprises a plate 25, extending from bolster to bolster and having an angle-bar 26 riveted to its lower edge and a similar bar 27 riveted to its upper edge.

This plate is stiffened at intervals by the vertical posts 28 and diagonal braces 29, which posts and braces are of any preferred metallic construction, being shown as angle-bars. The 5 side plates 25, together with the top and bottom angles and stiffening members, form plate-girders, being secured at their ends directly to the bolsters by means of the angle-bar 15.

The vertical posts 28 and diagonal braces 29 10 are placed inside of the sheets 25, with their projecting flanges directed toward the center of the car. At the body-bolsters two angle-bars 30 are employed to form the post, these angle-bars having their inwardly-projecting flanges secured together and form, in effect, a T-bar. A single T-bar might be used for this purpose. All of these posts and bars project upwardly above the plates 25 to the top of the car, and at the corners of the cars are 15 angle-posts 31, secured to the underframing and also rising to the top of the car. On the ends of the car intermediate the corners are other angle-posts 32, also rising to the top of the car, these being placed outside of the body. 20 The tops of the side posts are riveted to a top rail or plate 33, which is shown as an angle having its vertical flange lying outside of the posts and braces, and either riveted directly thereto or connected thereto by connection- 25 plates 34. The horizontal flange of this angle projects inwardly.

The vertical posts 28 and 30 and diagonal braces 29, together with the top chord 33 and bottom chord 25, form, in effect, a truss, which 30 is supported at its ends at the body-bolsters. The car sides therefore are of compound type, being partly plate-girders and partly trusses, and these serve the function of not only confining the lading but also carry a very mate- 40 rial part of the load.

The part of the car sides above the plate-girder 25 is filled in with metal of an open construction, such as the open-mesh expanded metal 35. At the middle of the car above the 45 plate-girder 25 is located a side door 36, which is composed of a rectangular frame of angle-bars and filled in with expanded metal. The sides of the car at the ends beyond the body-bolsters are formed by a triangular-shaped 50 plate 36^a and expanded metal 37 above the same, these parts extending from the posts 30 out to the corners of the car and from the top thereof down to the inclined floor-plates 11. The end of the car is formed by a top 55 angle-rail 40, expanded metal 41 below the same, and the end plate 42 below the expanded metal. This end plate has its lower edge flanged inwardly at 43 to form a support for the inclined floor-plates 11.

60 The inclined end portions of the car are supported by diagonal braces 44, riveted to the side plates 36^a and extending downwardly and riveted to the subside sills 45, which extend from the body-bolsters out to the corners of the car. A transverse floor-support

46 is located underneath the inclined floor-plates 11 and is supported by means of struts 47, extending diagonally downwardly and outwardly therefrom and having their lower ends secured to the draft-beams by means of 70 gusset-plates 48.

The inclined floor-plates 11 extend downwardly practically to the lower edge of the center sills. The center sills are covered by a longitudinal ridge formed of plates 50, which 75 are flanged at their upper edges and riveted together and which extend downwardly at the sides of the center sills and are then bent outwardly, as at 51, and form the inside hopper-sheets. Inclined plates 52 are riveted to 80 the lower edges of the car sides and form the outer hopper-sheets. Door-hinge lugs are secured to the sheets 51 and 52.

The end hopper-sheets 53 are riveted directly to the lower ends of the inclined floor- 85 plates 11 and are flanged at their lower edges to stiffen the same. The hoppers are divided transversely of the car by means of box-like diaphragms or transoms, which also serve to tie the car sides and center sills together and 90 stiffen the entire car-frame. These box diaphragms or transoms are each composed of a pair of plates 54, which extend from the center sills to the car sides and have their upper edges practically level with the upper edges 95 of the center sills. These plates have inwardly-turned flanges formed at their upper edges, to which is riveted a transverse connecting and cover plate 55, which extends continuously across the center sills, suitable openings being formed in the longitudinal ridge to permit the same to pass through. The plates 54 extend downwardly to the bottoms of the hopper and have their lower edges flanged to strengthen the same. Between the 100 plates 54, practically at a level with the bottom edge of the center sills, is a cross connecting member 58, which consists of a plate having its edges at the end bent to form 105 flanges 59, whereby it is riveted to the plates 54 and having its central portion flat and extending underneath the center sills and riveted thereto. This plate 58 serves as a cross- 110 connector and also serves in conjunction with the plates 54 and top connecting member 55 115 to make a box-girder. A brace 77 is secured between the diaphragm-plates 54 near the apices thereof.

The lower edges of the plates 54, as well as the end hopper-plates 53, are formed of inverted-V shape. There are two doors or sets of doors on each side of the car—an inner set 60, hung on the hinge-butts secured to the inner hopper-sheets 51, and an outer set 61, hung on the hinge-butts secured to the outer sheets 120 52. These sets of doors when closed bear against the lower edges of the end hopper-sheets 53 and diaphragms 54, thus forming a 125 V-shaped bottom for each compartment of the hopper. There are as many doors 60 and 61 130

as there are compartments to the hopper, four such doors being shown in each set in the particular car illustrated in the drawings. All of the doors 61 on each side of the car are connected by means of beams 64, so that, in effect, there is only a single door on the outside on each side of the car, and, if desired, the several door-sections 61 on each side of the car might be a single continuous door extending from end to end of the hopper. These outside doors 61 have connected thereto chains 65, which preferably are connected to the connecting-beams 64 and pass up around guide-sheaves 66, journaled between the diaphragm-plates 54 and thence outwardly and are wound on drums 67, secured to a winding-shaft 68, extending the length of the hoppers and journaled in suitable brackets 69, secured to the lower angle-bar 26 of the car side and the inclined outer hopper-sheets 52. By turning the shaft 68 all of the outer doors on that side of the car will be operated to open or close the same.

The different door-sections 60 for the several compartments of the hopper are connected in pairs by means of beams 70. Connected to these beams are chains 71, which pass over guide-sheaves 72, journaled between the diaphragm-plates 54, thence passing inwardly around guide-sheaves 73, secured to brackets depending from the center sills, and then upwardly and are wound on drums 74, located between the center sills. Two chains 71 from the pairs of doors on the two opposite sides of the car are wound on drums which are secured to a single winding-shaft 75, said shaft extending outwardly to one side of the car and being provided with an end 76 for the attachment of a crank or other winding means. Two such winding-shafts are shown for the car, and these are located in two of the hollow box-girder diaphragms. It will therefore be seen that there are four winding-shafts for the sixteen doors shown in the car, two of such winding-shafts extending longitudinally of the car at each side and each operating all of the outside doors on that side of the car and two transverse shafts, each serving to operate a set of double doors on both sides of the center sills. It will be obvious, of course, that the outside doors need not be connected together by means of the beams 64, but that each door might be connected separately to the winding-shaft, and it is also obvious that the central doors 60 likewise need not be connected together in pairs; but the arrangement shown in the drawings is preferred.

The car shown is provided with a roof, this being formed of a ridge pole or board 80 and sections 81, hinged thereto, thus forming a roof in which all parts can be turned up to give access to the interior of the car. This form of roof, however, is old and no claim is made therefor. The car may be constructed without a roof, if desired.

What I claim as my invention, and desire to secure by Letters Patent, is—

1. The combination of a center sill and car sides, a pair of longitudinally-arranged doors on each side of the center sill arranged to open in opposite directions, mechanism common to the inner doors on the two sides of the car for opening and closing the same, and independent mechanism for opening and closing the outer doors on the two sides of the car. 75

2. In a railway-car, the combination of a center sill and car sides, a pair of longitudinally-arranged doors on each side of the center sill, a longitudinally-arranged operating-shaft on each side of the car, connections between each of such longitudinal shafts and the outer door on that side of the car, a transversely-arranged operating-shaft, and connections between the same and the inner doors on both sides of the car. 85

3. In a railway-car, the combination of a center sill and car sides, a plurality of pairs of longitudinally-arranged doors on each side of the center sill, a longitudinal winding-shaft on each side of the car, connections between each of such shafts and all of the outer doors on that side of the car, a transversely-arranged winding-shaft or shafts, and connections between the same and a pair of inner doors on both sides of the car. 95

4. In a railway-car, the combination of a center sill and car sides, a plurality of pairs of longitudinally-arranged doors between the center sill and car sides, beams connecting adjacent outer doors on each side of the car to form, in effect, a single door, beams connecting two adjacent inner doors in pairs on each side of the car, a longitudinally-arranged winding-shaft on each side of the car, connections between the same and the outer doors on the same side of the car, transversely-arranged winding-shafts, and connections between the same and a connected pair of doors on both sides of the car. 105

5. In a railway-car, the combination of a center sill and car sides, a pair of longitudinally-arranged doors between the center sill and car sides, a hollow transverse support extending from the center sill to the car sides and having a pair of guide-sheaves secured thereto, a longitudinally-arranged winding-shaft at each side of the car, chains connected thereto and passing over one of the guide-sheaves in the transverse support and connected to the outside door on that side of the car, a winding-shaft extending through the transverse support, and chains wound thereon and passing over the other guide-sheave in the transverse support and connected to the inner doors on both sides of the car. 115

6. In a railway-car, the combination of the center sill and car sides, a hopper extending below the center sills, transverse hollow diaphragms dividing said hopper into sections, said diaphragms extending from the center 120

sills to the car sides, a pair of guide-sheaves journalized in said diaphragms, a pair of longitudinally-arranged oppositely-opening doors for each hopper-section, a longitudinal winding-shaft, chains connected thereto and passing over one of the guide-sheaves in the hollow diaphragm and connected to the outer doors, transverse winding-shafts extending through the hollow diaphragm, a chain wound thereon and passing over the other guide-sheave in the hollow diaphragm and connected to an inner door.

7. In a railway-car, the combination with a center sill and car sides, body-bolsters on which the same are supported, and hollow box-like diaphragms connecting said sills and car sides and lying mainly below the top of said center sill.

8. In a railway-car, the combination with the body-bolsters, of center sills and car sides supported thereon, box-like diaphragms connecting the center sills with the car sides, and a transverse connecting member secured to said diaphragms and extending continuously across the car-sills.

9. In a railway-car, the combination with the body-bolsters, of center sills and car sides supported thereon, inverted-trough-like diaphragms connecting the center sill and car sides, and a transverse connecting-plate extending underneath the center sills and being secured between the side walls of said diaphragm.

10. In a railway-car, the combination with the body-bolsters, of a center sill and car sides supported thereon, inverted-trough-like dia-

phragms connecting the center sills and car sides, a cross connecting-plate extending underneath the center sills and having its side edges flanged and riveted between the sides of said trough-diaphragms.

11. In a railway-car, the combination with a body-bolster, of center sills and car sides supported thereon, hollow box-like diaphragms connected to the center sills and car sides, the top and bottom member of said diaphragms extending continuously above and beneath the center sills.

12. In a railway-car, the combination of a center sill and car sides, of transverse hollow connecting means between the center sill and car sides, and dividing the bottom into a series of hoppers, doors for closing said hoppers, a winding-shaft and chains connected thereto and extending through said hollow connecting means and secured to said doors.

13. In a railway-car, the combination of a center sill and car sides, hoppers arranged on each side of the center sill, hollow diaphragms connecting the center sill and car sides, and dividing the hopper into sections, a pair of doors for each section, longitudinal beams for connecting said doors, winding-shafts, and chains connected thereto and extending through said hollow diaphragms and connected to said beams.

In testimony whereof I, the said JOHN M. HANSEN, have hereunto set my hand.

JOHN M. HANSEN.
